OSCILLATOR TUBE MOUNTING

Frederick H. Drake, Boonton, N. J., assignor to
Aircraft Radio Corporation, Boonton, N. J., a
corporation of New Jersey

Application October 17, 1946, Serial No. 703,868

14 Claims. (Cl. 178—44)

1

This invention relates to oscillator tube mountings, and more particularly to metal housings within which microwave oscillator tubes are supported in proper relation to microwave guide sections and are completely shielded. Tube mountings embodying the invention may be used with any microwave oscillator tube, such as a magnetron or Klystron, which operates at frequencies requiring the use of wave guides to conduct output away from the tube.

The invention will be described with respect to a housing and mounting for a Klystron oscillator tube known as JAN type No. 2K50. This microwave generator or oscillator tube is similar in general outer appearance to the "metal" tubes in common use in radio receivers, but differs from such tubes in that a glass disk or "window" is sealed in and at the center of the outer, radially-flanged end of the microwave oscillator tube. The output element of the microwave oscillator tube is a wave guide of rectangular cross-section at the inner face of the glass window, and the flanged end of the tube has a notch in its outer edge for cooperation with a pin or key on the housing to align the rectangular wave guide of the tube with a rectangular wave guide section which is connected to the housing.

The several prior constructions for mounting such oscillator tubes have not been entirely satisfactory as they were relatively complex and bulky, and they did not permit a rapid removal and replacement of the tubes. The mechanical problems involved are the alignment of the wave guide of the tube and of the output line from the microwave generator, and the axial adjustment of the tube to compensate for manufacturing variations in the length of tubes.

Objects of this invention are to provide shielded mountings for microwave oscillator tubes which are of relatively simple mechanical construction to facilitate removal and replacement of the tubes. Objects are to provide mountings which afford an automatic angular and axial adjustment of the oscillator tubes into proper position with respect to the associated wave guide section, and which impose no stress upon the tube per se, upon the tube socket or upon the leads to the tube socket. A further object is to provide a mounting of the type stated in which the shielding housing is formed as a cylindrical shell in which the tube socket is supported, a cover which is rigidly secured to a short wave guide section which is detachably coupled to the rigidly positioned wave guide system, and a gland nut for securing the housing cover to the cylindrical shell.

2

cylindrical shell; the tube socket being floated within the shell for limited axial and angular movement to permit alignment of the tube output element with the wave guide section.

These and other objects and advantages of the invention will be apparent from the following specification when taken with the accompanying drawings in which:

Fig. 1 is an elevation, with parts in section, of an oscillator tube mounting embodying the invention;

Fig. 2 is a section on the line 2—2 of Fig. 1;

Fig. 3 is a perspective view of the interior of the cover; and

Fig. 4 is an end elevation of a microwave oscillator tube.

In the drawings, the reference numeral 1 identifies a cylindrical metal shell which forms the major portion of the housing and shield for a microwave oscillator tube T, the shell having external threads at its open upper end upon which a gland nut 2 may be turned to secure a cover 3 upon the shell. The lower end of the cover telescopes within the shell 1, and the flange which seats against the end of the shell is engaged on its outer side by the inturned rim of the nut. The cover 3 is rigidly secured to a short section 4 of wave guide tubing of rectangular cross-section which is bent through 90° and terminates in a vertically arranged flange 5 which is detachably connected to the end of a rigidly mounted wave guide system S by a gland nut 5'. Other quickly-detachable coupling mechanism may be employed, but it is essential that the construction be such that the cover 3 and wave guide section 4 can be lifted vertically when the gland nuts 2 and 5 are backed off.

The end flange f of the tube T has a circumferential notch n in predetermined angular position with reference to the tube output element e which is of rectangular cross-section and positioned beneath a glass window w. As shown in Fig. 4, the notch n is in radial alignment with the major axis of the output element e.

The housing cover 3 and wave guide section 4 may be connected in any desired manner but preferably, as shown, by a bushing 6 which is secured to the cover 3 by a pressed flange 7 and which has a bore into which the wave guide 4 is inserted and soldered. The inner end of the bushing 6 is counterbored to provide a shallow cylindrical chamber 8 having a flaring entrance 9 for guiding the flange f of the tube T into the chamber. A pin or key 10 extends longitudinally of the peripheral wall of the chamber 8 for co-

operation with the notch *n* of the tube flange to insure alinement of the rectangular wave guide funnel *e* of the tube *T* with the rectangular wave guide passage through the bushing *6* and wave guide tube *4*. An annular recess *11* which is cut or otherwise formed in the end wall of the chamber *8* serves as a wave guide choke.

The tube *T* has terminal prongs of conventional design, not shown, for mounting the tube in a socket *12* and for connecting the tube elements with the socket contacts *13*. The socket is secured to an annular plate *14* in conventional manner according to the particular design of the socket, and the plate is "floated" within the shell *1* for axial movement between stops which are shown as sets of screws *15* and *16* threaded through the wall of the shell *1*. The plate *14* and socket *12* are pressed towards the outer set of screws *15* by a coiled spring *17* which is seated upon another set of screws *18* which are threaded through the shell *1*. The socket plate has one or more peripheral notches *19* into which longitudinal keys *20* of the shell *1* project to permit limited angular movement of the socket plate *14* within the shell.

The outer end *21* of the shell *1* is of somewhat enlarged diameter to provide a thicker, and thereby a mechanically stronger, wall in which a plurality of terminals *22* are mounted. The particular construction of the terminals and their supporting elements forms no part of the present invention. The illustrated terminal construction is of the type which is shown in greater detail in my copending application Ser. No. 676,682, filed June 14, 1946.

The leads *23* which connect the inner ends of the terminals *22* to the several socket contacts *13* are preferably formed as multiple turn coils of small diameter to insure great flexibility and substantial elimination of stress when the socket *12* moves angularly and axially of the shell *1*. The outer end of the shell *1* is closed by a threaded cap plate *24* having two projecting lugs *25* against which any straight edged device, such as a ruler or the shank of a screwdriver, may be placed to turn the cap plate into and out of the shell *1*.

The housing shell *1* has a short threaded section *26* between the outer end section *21* and the remainder of the shell, the threaded section being of somewhat less diameter than the end section *21* to leave a small radial shoulder *27* at the inner end of the larger diameter section *21*. The housing shell *1* extends through a chassis *28* and is rigidly secured in place by a nut *29* which is turned down upon the threaded section *26* to draw the radial shoulder *27* into firm engagement with the lower face of the chassis. The nut *29* may have longitudinal grooves *30* at its inner surface to clear the ends of the screws *15*, *16* and *18* of the floating socket assembly.

The microwave tube may be readily removed and replaced by another tube in the following manner. The nut *2* is backed off to release the cover *3* from the shell *1*, and the nut *5* is turned back to release the short wave guide section *4* from the rigidly supported wave guide system *S*. The cover *3* and wave guide section *4* may then be lifted vertically to afford access to the interior of the housing shell *1*. The tube *T* may then be removed from the socket *12*, and a new tube inserted. The cover *3* and attached wave guide section *4* are then replaced, the cover being turned angularly into such position that the key *10* enters the notch *n* of the tube as the cover is lowered upon the tube flange *f*. The nut *2* is turned down loosely and the cover *3* is adjusted

angularly, if such adjustment is necessary, to bring the terminal flange *5* of the wave guide section *4* into alinement with the wave guide system *S*. The output element *e* of tube *T* remains in alinement with the wave guide passage of section *4* as it is keyed to the cover *3*, the tube *T* and its socket *12* turning with the cover *3* during the slight angular adjustment of the latter which may be necessary to couple the wave guide section *4* to the microwave system. The upper end of the tube *T* is firmly seated on the end wall of the chamber *8* of the cover *3* by the spring *17* which bears against the socket mounting plate *14*.

It is to be understood that the invention is not limited to the particular embodiment herein shown and described as various changes which may be made in the several parts, and in their relative sizes, shapes and relationships, fall within the spirit and scope of the invention as set forth in the following claims.

I claim:

1. A mounting for a microwave oscillator tube of the type having a flanged top beneath which there is a wave guide output element of rectangular cross-section, and said top being provided with alinement means; said mounting comprising a shell with an open end, a cover and means for detachably securing the same upon the open end of said shell, a wave guide tube of rectangular cross-section rigidly secured to said cover, said cover having a passage therethrough of rectangular cross-section forming an extension of the passage of said tube, the inner face of said cover being recessed to receive the flanged top of an oscillator tube, means at the inner face of said cover to engage the alinement means of a tube top to aline the oscillator tube output element with the passage of said cover, a tube socket within said shell, and means supporting said tube socket for limited angular movement.

2. A mounting as recited in claim 1, wherein said cover is telescoped with said shell and has a flange seated upon the end thereof, and said securing means is a gland nut threaded upon said shell and engaging the outer side of the cover flange.

3. A mounting as recited in claim 1, wherein said means supporting said socket includes a circumferentially notched plate carrying said socket, and means on said shell and extending into a notch of said plate to limit angular movement of the plate and socket.

4. A mounting for a microwave oscillator tube of the type having a wave guide output element of rectangular cross-section, said mounting comprising a housing shell with an open end, a tube socket and means supporting the same in said shell for limited angular movement, said socket being spaced from the open end of the shell to leave only the outer end of an oscillator tube outside of the shell, a cover for the open end of the housing shell, a wave guide tube of rectangular cross-section rigidly secured to said cover, means on said cover for engagement with cooperating means on an oscillator tube to aline the output element of a tube with the passage of said wave guide tubing, and means detachably securing said cover to said shell.

5. A mounting for a microwave oscillator tube of the type having a wave guide output element of rectangular cross-section and an end flange with alinement means in predetermined angular relation to the axes of the output element, said mounting comprising a housing including a shell

section and a cover section, a tube socket and means supporting the same within said shell section for limited angular movement, a wave guide tube of rectangular cross-section rigidly secured to said cover, alinement means at the inner face of said cover section for cooperation with the alinement means of an oscillator tube to locate the output element thereof in alinement with the passage of said wave guide tube, means at the outer end of said wave guide tubing for detachably connecting the same to a wave guide system, and means for securing said cover section to said shell section.

6. A mounting for a microwave oscillator tube of the type having a wave guide output element of rectangular cross-section and alinement means; said mounting comprising a cylindrical shell having an open upper end, a cover having a wave guide passage of rectangular cross-section therethrough, said cover having means for cooperation with the alinement means of an oscillator tube to aline the output element thereof with the wave guide passage of the cover, means for detachably securing said cover across the open end of said shell, a tube socket within said shell and having contacts extending from its lower face, means supporting said socket for limited angular and axial movement with respect to said shell, a set of terminals extending through and insulated from said shell, the inner ends of said terminals being axially spaced from said socket contacts, leads connecting said socket contacts to said terminals, said shell having an upwardly facing circumferential flange above said terminals and an externally threaded section above said flange, and a nut for threading upon said threaded section of the shell to secure the shell to a chassis having an opening therethrough which passes said threaded section but not said circumferential flange.

7. A mounting as recited in claim 6, wherein said means supporting said socket for limited axial movement includes cooperating sets of axially spaced stops carried by said shell, and spring means urging said socket towards the upper set of stops.

8. A mounting as recited in claim 6, wherein said means supporting said socket includes a circumferentially notched plate carrying said socket, and longitudinal ribs on said shell and extending into the notches of said plate.

9. A mounting for a microwave oscillator tube of the type having a wave guide output element of rectangular cross-section; said mounting comprising a cylindrical shell having a socket therein for receiving an oscillator tube, a cover for the shell and having a wave guide passage of rectangular cross-section extending axially therethrough, a wave guide tube secured to said cover in alinement with said passage and curved to extend laterally, means for detachably securing said cover across an end of said cylindrical shell, and coupling means on the end of said wave guide tube for detachably connecting the same to

a wave guide system, said coupling means when released being separable from the wave guide system by movement of the cover and wave guide tube axially of said cylindrical shell.

10. A mounting as recited in claim 9, and for use with oscillator tubes of the type which terminate in a circumferentially notched flange extending around a window beneath which the output element is located, wherein the inner face of the cover is recessed to receive an oscillator tube flange and has a key for mating with the notch thereof.

11. A mounting as recited in claim 9, wherein terminals extend through said shell adjacent the ends thereof opposite said cover, leads extend from the inner ends of said terminals to said socket, and a cap is threaded to said shell to close said opposite end thereof.

12. A mounting as recited in claim 9, wherein said cylindrical shell has a circumferential flange facing towards said cover and is externally threaded adjacent said flange and at the side thereof toward said cover, and a nut is threaded upon said threaded section for cooperation with said flange to secure the shell to and extending through a chassis.

13. In a tube mounting, a removable closure for one end of said shell and having a wave guide passage extending axially therethrough, said end closure having a conical seat at the end of said wave guide passage for engagement by a cylindrical outer terminal at the tip of an oscillator tube, a cylindrical shell, a tube socket within said shell and carried by a disk, axially spaced sets of stop means projecting into said shell at opposite sides of said disk, and spring means within said shell at the inner side of said socket yieldingly urging said disk and socket towards the outer set of stop means.

14. In a tube mounting, a closure for one end of said shell and having a wave guide passage extending therethrough, said end closure having a conical seat for engagement by a cylindrical outer terminal of an oscillator tube, a cylindrical shell, a tube socket within said shell and carried by a circumferentially notched disk, axially spaced sets of stop means projecting into said shell at opposite sides of said disk, spring means within said shell at the inner side of said socket yieldingly urging said disk and socket towards the outer set of stop means, and ribs on said shell and extending into said notches of the disk.
